UNITED STATES PATENT OFFICE.

DAVID L. TEMPLE, OF FLORAL PARK, NEW YORK, ASSIGNOR TO WESTERN ELECTRIC COMPANY, INCORPORATED, OF NEW YORK, N. Y., A CORPORATION OF NEW YORK.

AUTOMATIC TELEPHONE SYSTEM.

Application filed December 29, 1925. Serial No. 78,184.

This invention relates to a simplified method of supervision in telephone systems but more particularly to cord circuits.

Heretofore, supervision has been provided by means of lamps controlled by relays located in the cord circuit under control of other relays in the trunk or line circuits with which the cord is used. A feature of this invention is that the relays in the cord circuit are eliminated and the supervisory lamps are controlled by means of a double wound sleeve relay in either the trunk or line circuit, one winding of which is shunted in and out of circuit by the line relay, the shunted winding being of such a resistance that the lamp will be extinguished when the shunt is removed.

It is the object of this invention to provide improved and simplified supervisory circuits for telephone exchange systems.

A feature of this invention is the use of a tone under the control of a cord circuit key to notify the operator that the called subscriber has answered and that the key has not been released.

A clear conception of the invention may be had from the drawings and description in which:

Fig. 1 discloses a trunk circuit incoming from selector bank arranged for coin collect and refund.

Fig. 2 discloses a trunk circuit incoming from a connector bank.

Fig. 3 shows an operator's cord circuit embodying the features of this invention.

Fig. 4 shows a trunk circuit for repeating the pulses from the dial in the operator's cord circuit to a selector circuit.

Fig. 5 is a rural subscriber's line circuit with common battery supervision.

Fig. 6 discloses a rural subscriber's line circuit with magneto supervision.

The trunk circuit disclosed in Fig. 1 is used with a step-by-step selector circuit and is arranged for collection or refund of coins at the calling subscriber's station. This trunk may be connected to any one of the

trunk or line circuits disclosed in Figs. 4, 5 or 6 by means of the cord circuit disclosed in Fig. 3. Figs. 1 and 2 are arranged to give 50 supervision on the answering end of the cord circuit in Fig. 3 and the trunk and line circuits of Figs. 4, 5 and 6 are arranged to give supervision on the calling end of the cord circuit. Jacks 315 and 316 are provided for connecting an operator's telephone headset to cord C.

A clearer conception of the operation and the features of the invention may be obtained from the following detailed description. When a selector, such as is disclosed in the patent to R. L. Stokely No. 1,474,008 issued November 13, 1923, selects the trunk circuit ST a circuit is closed from ground through the right winding of relay 101, upper back contact of relay 104, conductor 110, through the selector, back over conductor 111, lower back contact of relay 104 to battery through the left winding of relay 101. Relay 101 operates and closes an obvious circuit for relay 102. Relay 102 operated lights lamp 121 over a circuit from battery through the outer right front contact of relay 102, inner left back contact of relay 105, to ground through lamp 121. Relay 102 also 65 connects tone current from source 123 through lamp 106, right back contact of relay 105, inner right front contact of relay 102 to conductor 111 and thence over the ring 70 side of the line to the calling subscriber's line. Relay 102 at its left contact also grounds the sleeve conductor 112 of the trunk to mark the trunk busy and holds the preceding selector switches operated. The operator, noting lamp 121 lighted, inserts the 75 plug 320 of cord C in the jack 120, thereby operating relay 105 over a circuit from ground through the windings of relay 105, sleeves of jack 120 and plug 320 to battery 80 through lamp 321. The resistance of the windings of relay 105 in series is such that lamp 321 will not light. The operation of relay 105 opens the circuit for lamp 121 at its inner left contact and also removes the 85

ringing induction and holds relay 102 operated. The operator now operates the talking key 305 and ascertains the number of the desired line.

5 It will first be assumed that the desired subscriber is in a machine switching office which is accessible over the dial trunk DT of Fig. 4. The operator touches the tip of plug 330 to the sleeve of jack 410. If the trunk is busy, battery will be connected to the sleeve of jack 410 thereby causing the operation of relay 309 in a manner well known in the art. The operation of relay 309 closes an obvious circuit through coil 312 and the left winding 10 of tone coil 310 thereby giving the operator a busy click in her headset which is plugged up in the jacks 315 and 316.

We will assume, however, that the trunk DT is idle. The operator then inserts the 20 plug 330 into jack 410 thereby operating relay 403, from battery through lamp 331, sleeves of plug 330 and jack 410 through the right winding of relay 403 to ground on the back contact of relay 405. The operation of 25 relay 403 closes a circuit for operating relay 404 from ground on the left contact of relay 403, outer right normal contact of relay 402, to battery through the winding of relay 404. The trunk circuit DT is now in condition for 30 dialing. The operator throws dialing key 303 and connects conductors 317 and 318 to the tip and ring leads, respectively, of the cord circuit. Relay 401 is also operated over a circuit from ground on contact 322 35 of dial 306, conductor 317, inner upper alternate contact of key 303, tips of plug 330 and jack 410, contact 417 of relay 412, contact 419 of relay 401, to battery through the winding of relay 401. Relay 401 operated 40 closes conductors 413 and 414 through to conductors 420 and 421 which are connected to a step-by-step selector (not shown). Relay 401 locks under control of relay 403 which is under control of the cord circuit 45 C. Relay 402 also operates at this time from ground through resistance 327, outer left contact of relay 308, conductor 318, lowermost alternate contact of key 303, rings of plug 330 and jack 410, contact 418 of relay 412, to battery through the left winding of relay 402. The operation of relay 402 closes 50 a new operating circuit for relay 404 from ground on contact 322 of dial 306, conductor 317, tips of cord 330 and jack 410, contact 417 of relay 412, right outer front contact of relay 402, to battery through the winding of relay 404, and short circuits at 55 its left contact the relay 405 thereby reducing the impedance of the bridge across the 60 trunk conductors.

When the operator operates the dial 306, relay 404 follows the impulses and opens and closes a bridge across trunk conductors 420 and 421 extending through contacts of relays 65 402 and 404. This in turn controls the op-

eration of the selector switch in a manner well known in the art. When dial 306 was moved off normal the alternate contact of spring 307 was closed thereby operating relay 308 over a circuit from battery through 70 the left winding of relay 402, contact 418 of relay 412, rings of jack 410 and plug 330, lower alternate contact of dialing key 303, conductor 318, alternate contact of spring 307 of dial 306 to ground through the right winding of relay 308. Relay 308 operated, locks in an obvious circuit to ground on the uppermost alternate contact of key 303. The operation of relay 308 disconnects resistance 327 from conductor 318 and prepares 75 an operating circuit for relay 313. Relay 313 does not operate at this time as its circuit is not complete. Upon the completion of dialing relay 402 deenergizes.

When the desired line has been selected and the called subscriber has answered, reversed battery current is transmitted over trunk circuit 420, 421 in a manner well known in the art and polarized relay 405 operates, in turn operating relay 412 over 80 an obvious circuit. Relay 412 operated connects conductors 413 and 414 directly through to the tip and ring of jack 410. Before battery was reversed in the selector circuit, ground was connected to conductor 420 and battery to conductor 421. When the battery was reversed, the ground which is now connected to conductor 421 will operate relay 313, if the operator has not restored the dialing key 303. Relay 313 operates over a circuit from ground on conductor 421, lower contact of relay 401, conductor 414, contact 416 of relay 412, rings of jack 410 and plug 330, lower alternate contact of key 303, conductor 318, normal contact of spring 307 of dial 306, right front contact of relay 308 to battery through the winding of relay 313. The operation of relay 313 connects a tone through coil 311, to the operator's headset notifying her that the dialing key 303 should be restored. Relay 313 releases when the dialing key is restored thereby cutting off the tone. The operation of relay 405 also removes the shunt from 90 around the left winding of relay 403 thereby increasing the resistance of the circuit through lamp 331, and extinguishing the lamp as an indication that the called subscriber has answered. Should the call be from a coin box line, the operator operates coin collect key 118. The operation of key 118 operates relay 104 over an obvious circuit and connects coin collect current to conductors 110 and 111, from coin collect source 116 through the winding of relay 117, lamp resistance 119, alternate contact of key 118, through both alternate contacts of relay 104 to conductors 110 and 111.

If the call is for a party for which a charge is not to be made, there is no battery 130

reversal over trunk circuit 420, 421. Therefore, lamp 331 will remain lighted. When the lamp remains lighted and the operator hears the called subscriber respond, this is a signal to the operator that the coin should be refunded and refund key 109 is operated, operating relay 104 over an obvious circuit. Relay 104 connects coin refund source 114 through the winding of relay 113, lamp 108, alternate contact of key 109, contacts of relay 104 to conductors 110 and 111.

When the called subscriber replaces the receiver on the switchhook, relay 405 is released thereby connecting a shunt around the left winding of relay 403, allowing lamp 331 to light as a disconnect signal. This is only true on a call through a station for which a charge is made. If the call is from a no-charge line, the operator listens in for the subscriber to hang up at which time she withdraws plug 330 from jack 410. The release of relay 405 also opens the circuit of relay 412 opening the talking conductors. When the operator withdraws plug 330 from jack 410, relay 403 also releases in turn releasing relay 401 and restoring the circuit to normal. When the calling subscriber replaces the receiver on the switchhook, relay 101 releases, thereby connecting a shunt around the right winding of relay 105 from ground on the back contact of relay 101. This shunt removes resistance from the sleeve circuit and allows lamp 331 in the cord circuit to light as a disconnect signal. The release of relay 101 also opens the circuit for relay 102 which releases and removes the busy ground from the sleeve 112. The trunk circuit ST now restores to normal, releasing the selector which extended the calling line into connection with the trunk.

A call incoming over a trunk such as CT from a connector circuit and outgoing to a common battery line circuit will next be considered. When a connector such as disclosed in the patent to R. L. Stokely above referred to seizes terminals connected to conductors 210, 211 and 212, ringing current will be connected to relay 201 causing it to operate and in turn operate relay 202 from ground on the inner contact of relay 201, left contact of relay 204 to battery through the winding of relay 202. Relay 202 is held operated to ground on the sleeve conductor 212 over its right front contact. The operation of relay 202 lights lamp 221 over an obvious circuit. Lamp 221 is an indication to the operator of an incoming call. The operator then inserts plug 320 into jack 220 which is associated with lamp 221 thereby operating relay 204 over a circuit from battery through lamp 321, sleeves of jack 220 and plug 320, left winding of relay 204 to ground on the back contact of relay 203 and the outer front contact of relay 201. The right winding of

relay 204 is shunted by ground on the back contact of relay 203. The operation of relay 204 connects relay 203 across conductors 210 and 211 thereby operating the ringing trip relay in the connector. The removal of ringing current releases relay 201 and operates relay 203 from battery in the connector. The operation of relay 203 and the release of relay 201 removes the shunt from around the right winding of relay 204 thereby extinguishing lamp 321. Relay 204 also connects holding ground to conductor 212 over the back contact of relay 202 and the inner front contact of relay 204, for the purpose of holding the connector.

The operation of cord circuit C is the same as described above until plug 330 is inserted in jack 510. At this time, relay 503 will operate from battery through lamp 331, sleeves of plug 330 and jack 510, left winding of relay 503 to ground at the right contact of relay 502. Relay 503 operates and lamp 331 lights. Ringing current and ground are connected to the tip and ring of cord C by the operation of key 304, and relay 504 operates in turn operating relay 505 which cuts the line relay 501 off of the line. The ringing current also rings the bell at the called station.

When the operator releases the ringing key 304, relay 504 releases restoring relay 505 which connects line relay 501 across conductors 520 and 521. When the called subscriber at station 512 answers, relay 501 operates from battery through its left winding, right back contact of relay 505, conductor 521, subscriber's station 512, conductor 520, left back contact of relay 505 to ground through the right winding of relay 501. Relay 501 operated, operates relay 502 over an obvious circuit. The operation of relay 502 removes the shunt from around the right winding of relay 503 extinguishing lamp 331 as an indication that the subscriber has answered. Should the subscriber flash the switchhook, relay 501 will follow the switchhook in turn operating and releasing relay 502 which will open and close the shunt around the right winding of relay 503, causing lamp 331 to flash as a signal to the operator.

When the called party replaces the receiver on the switchhook, relay 501 will release in turn releasing relay 502 which will replace the shunt around the right winding of relay 503 causing lamp 331 to light as a disconnect signal. When the operator withdraws plug 330 from jack 510, relay 503 will release and restore the circuit to normal. When the calling subscriber replaces the receiver on the switchhook, the intervening switches will release except the connector which remains operated until the operator withdraws plug 330 from jack 220 opening

the circuit of relay 204. The release of relay 204 opens the circuit for relay 203 and releases the connector.

If on a call from a toll board the toll operator should desire to ring while the connection is up, relay 201 will respond to the ringing current and short-circuit the high resistance winding of relay 204 and allow lamp 221 to operate as an indication to the operator.

We will now consider a call from either of trunks ST or CT through the cord C to the magneto line circuit ML. The operation of the two trunks and the cord circuit is the same as described above until plug 330 is inserted in jack 610. At this time relay 602 operates from battery through lamp 331, sleeve of plug 320, sleeve of jack 610, windings of relay 602 to ground. Lamp 331 does not light but relay 602 operates. The operator now operates ringing key 304 which closes a circuit from ground on its upper alternate contact, upper normal contact of dial key 303, tips of plug 330 and jack 610, winding of relay 601, rings of jack 610 and plug 330, lower normal contact of dial key 303, the lower normal contact of key 304 to ringing source 302. Relay 601 operates and places a shunt across the right winding of relay 602 allowing lamp 331 to light. The operator after ringing the called subscriber releases the ringing key and throws the talking key 305 to listen for the response of the called subscriber. When the ringing key is released, relay 601 is released in turn removing the shunt from around the right winding of relay 602 extinguishing lamp 331. When the called subscriber rings off, relay 601 again operates shunting the left winding of relay 602, causing lamp 331 to light as an indication to the operator that the called party has disconnected. When the plug 330 is removed from jack 610, the operated relays release restoring the circuit to normal.

When the subscriber at substation 512 initiates a call, relay 501 operates over the back contacts of cut-off relay 505 and the line loop and closes an obvious circuit for relay 502. Relay 502 in turn closes a circuit over its left contact and the back contact of relay 503 for lamp 511. The operator noting the illumination of lamp 511 inserts plug 320 in jack 510 thereby causing the operation of relay 503 in series with lamp 321. Relay 503 operating opens the circuit of lamp 511 extinguishing it. Since relay 502 is at the time energized the shunt around the right winding of relay 503 is open and the full resistance of relay 503 is inserted in the circuit of lamp 321 whereby lamp 321 is not lighted.

If the subscriber at station 622 initiates a call by operating his magneto, relay 601 operates closing a circuit for relay 603 from

battery contact of relay 602, winding of relay 603 to ground at the left contact of relay 601. Relay 603 upon operating locks to ground over its right contact and at its left contact closes a circuit for lighting lamp 611, extending from battery at the contact of relay 602, left contact of relay 603 to ground through lamp 611. The operator noting the illumination of lamp 611 inserts plug 320 in jack 610 thereby causing the operation of relay 602 in series with lamp 321. Relay 602 operating opens the circuits of relay 603 and lamp 611. Lamp 321 does not light, as following the release of relay 601 when the subscriber ceases ringing, both windings of relay 602 are in the circuit of lamp 321.

What is claimed is:

1. In a telephone system, a cord circuit, a line, a signal lamp for said line, a ring down relay for said line, a double wound cut-off relay, a third relay controlled by said ring down relay, a circuit for said lamp extending through contacts of and controlled by said cut-off relay and said third relay, a supervisory lamp in said cord circuit, a circuit for said latter lamp extending through both windings of said cut-off relay, the resistance of said winding being such that said supervisory lamp does not light, and a shunt for one winding of said cut-off relay controlled by said ring down relay whereby said supervisory lamp becomes lighted.

2. In a telephone system, a cord circuit, a line, a ring down relay for said line, a double wound cut-off relay, a supervisory lamp in said cord circuit, a circuit for said lamp extending through both windings of said cut-off relay, the resistance of said windings being such that said lamp does not light, and a shunt adapted to be closed through a contact of said ring down relay for shunting one winding of said cut-off relay whereby said lamp becomes lighted.

3. In a telephone system, a cord circuit, an operator's telephone circuit, a called line, a key, a tone source for indicating to the operator the failure to release the key after the called station has answered, a relay under control of said key for connecting said tone source to said operator's circuit, and means under control of the called station for causing the operation of said relay until said key has been released.

4. In a telephone system, a cord circuit, an operator's telephone circuit, a called line, a key in said cord circuit, a tone source for indicating that the key has not been released after the called station has answered, a relay under control of said key, and a second relay under control of the called station and of said first relay unless said key has been released for connecting said tone to said operator's circuit.

5. In a telephone system, a cord circuit, an operator's telephone circuit, a called line, an operator's apparatus, a key in said cord circuit for connecting said apparatus to said cord circuit, a tone source for indicating that the key has not been released after the called station has answered, and a relay controlled by the response of the called subscriber under

the joint control of said key and of said apparatus for connecting said tone source to 10 said operator's circuit.

In witness whereof, I hereunto subscribe my name this 26th day of December, A. D. 1925.

DAVID L. TEMPLE.
